WARP KNITTING MACHINE

Frank J. Ford, Worcester, Mass., assignor of one-half to Harry Whittaker and Stanly Whittaker, both of Oxford, Mass.

Application June 14, 1940, Serial No. 340,419

19 Claims.

(Cl. 66—9)

The subject matter of the present invention relates to the art of machine knitting, and more particularly to warp knitting machines which may be used for knitting pads or padding comprising rows of relatively large diameter rovings knit together by threads across and around the rows, and having yarn knitted in lengthwise of the rows.

Objects of the invention include the provision of a machine which may be used for knitting the above-mentioned padding but is not limited to this use; the provision of a knitting machine having means for feeding and guiding a roving and a plurality of warp threads to the needles, and means for feeding, guiding, and knitting yarn in combination therewith; the provision of a warp knitting machine having two sets of needles and a set of new and improved warp thread guiding jacks, wherein said jacks are automatically operated in timed relation to said sets of needles; the provision of a warp knitting machine for the above-mentioned purposes and having new and improved roving and yarn guides, guards, carriers, and operating means; and the provision of a warp knitting machine which may be used to knit goods in the absence of a roving.

Other objects and advantages of the invention will appear hereinafter.

Reference is to be had to the accompanying drawings, in which

Fig. 1 is a side elevation of a machine embodying the present invention, with parts broken away;

Fig. 2 is a plan view as seen from line 2—2 in Fig. 1;

Fig. 3 is a plan view partly in section on line 3—3 in Fig. 1;

Fig. 3a is a detail view of a modified yarn carrier;

Fig. 4 is a view in elevation, parts being in section, of the upper end of the dial shaft and appurtenant parts;

Fig. 5 is a sectional view thru the cylinder, showing a part of the dial in section also;

Fig. 6 is a sectional view thru the lower end of the dial shaft and the dial;

Fig. 7 is a plan view of a cam section for the dial needles and the jacks;

Fig. 8 is a partial plan view of the cylinder cam ring;

Fig. 9 is a partial plan view of the dial;

Fig. 10 is an enlarged plan view of a section of the cylinder, parts being broken away;

Fig. 10a is a detail of a modified yarn guide;

Fig. 11 is a section on line 11—11 in Fig. 10;

Fig. 12 is a side elevation of a yarn guide, looking in the direction of arrow 12 in Fig. 10;

Fig. 13 is a side elevation of a yarn bracket, looking in the direction of arrow 13 in Fig. 3;

Fig. 14 is a view in elevation of a cylinder cam section;

Fig. 15 is a section on line 15—15 of Fig. 14;

Fig. 16 is a section on line 16—16 of Fig. 14;

Fig. 17 is an enlarged front elevation of a jack and dial needles, the dial being broken away;

Fig. 18 is a plan view of the parts of Fig. 17, looking in the direction of arrow 18 in Fig. 17;

Fig. 19 is a detail view in front elevation of a series of jacks and a warp guide therefor;

Figs. 20—23 are diagrammatic views showing the interaction of a jack and a cylinder needle;

Figs. 24 and 25 show the front and rear faces of a padding which may be made by the machine;

Fig. 26 shows a jack in plan, as it appears when not in its slot; and

Figs. 27—32 inclusive illustrate diagrammatically the coaction of the cylinder needles with the warp yarn carriers.

15 In the drawings, the numeral 12 generally indicates an angle iron framework forming a support for the knitting machine here illustrated in a preferred embodiment of the invention. The framework 12 may be supported on legs or other

20 means, not shown. The framework is not completely disclosed, as it may take various forms as becomes necessary, but at 12a in the present instance, it provides for a bearing 14 for a main drive shaft 16. This shaft is adapted to be driven

25 by power as by a belt 18, and carries a pulley 20 which is connected by a belt to drive an overhead shaft 22, journaled in the framework 12 at 12b, shaft 22 carrying a gear 24. Shaft 16 carries a gear 26 which rotates the cylinder cam

30 ring 72, while gear 24 rotates the dial cap plate 48, the dial and cylinder needles being located as is usual in slots in their respective supports.

35 Mounted on a part of the framework 12 is an overhead X-shaped arc 28 integrally supporting a hollow vertical hub 30 thru which extends the dial shaft 32, this shaft supporting the dial 34 at its lower end. The top of the dial shaft 32 has integrally formed thereon the screw-threaded portion 36 which engages a large nut 38. The

40 dial shaft is hung from the arch 30 by means of the nut 38 which rests on the hub 30 of the arch 28. It will be clear that the dial shaft and therefore the dial can be vertically adjusted by turning the nut by the handbars 40.

The gear 24 on the shaft 22 meshes with a ring gear 42 adjustably secured to a sleeve 44, as shown in Fig. 4, by the screws 46. A bearing pad is provided between the dial shaft and the sleeve, and the latter extends down to a point

45 spaced from the end of shaft 32, where it carries the dial cap plate 48, so as to rotate the latter therewith. Adjacent the end of shaft 32, the dial bed 50 is bolted thereto, as shown in Fig. 6, there being a thrust bearing 52 located

50 between the sleeve 44 and the shaft.

55

50

55

50

Thus it will be seen that the dial shaft 32 does not rotate, but carries the dial, both the rotary dial cap plate 48 and the stationary dial bed 50. Turning the nut 38 will vertically adjust the dial as a whole, without disturbing the relation of the cap plate 48 and bed 50, while it is only necessary to loosen screws 46 to allow for the adjustment of sleeve 44 with relation to gear 42.

Supported on the same bolts that locate the arch 28, but on the underside of the framework part 12, are a plurality of horizontal rods 54 which carry the depending bars 56, supporting the warp thread guide 58. This guide is circular in form, surrounding the sleeve 44, and comprises top and bottom apertured plates 60, to 15 guide the threads 62 as seen in Fig. 1, said plates being interconnected by rods 64. The threads 62 wind off the usual thread carriers, not shown, and are passed thru the eyes of a further guide plate 66, which extends beyond the dial, as indicated in Fig. 5, and this guide 66 is circular in form, conforming to the dial, being supported from the lower guide plate 60 by bars 68.

Angle iron part 12c stationarily supports the ring 70, which is cut away to allow the gear 26 to extend therethru to mesh with teeth on the cylinder cam ring 72 to drive the latter (see Fig. 5). The rings 70 and 72 extend all the way around the machine as shown in Figs. 3 and 8, and the cam ring 72 slidably rests on the stationary ring 70 and is guided thereby. The cylinder 74 is stationarily secured to the ring 70 and vertically carries the cylinder needles 76 in the usual slots.

Bolted or otherwise secured to the traveling cam ring 72 are a plurality of evenly spaced bracket arms 78, each arm mounting a vertical rod 80, on each of which is angularly adjustably mounted an apertured rod 82. Thru each aperture extends a hollow, generally cylindrical tube 84 which has a cut-away portion at 86, forming a kind of nozzle for guiding the roving 88, see Fig. 10.

Each rod 80 also carries a bracket 90 which extends radially of the dial and each bracket 90 supports a disc 92 at its other end. The discs 92 carry the roving baskets 94, in which the coils of the roving are placed, with the end thereof passing down from the basket and thru the guides 84, whence they are fed to the machine, to a position behind the cylinder needles.

Each rod 80 in addition carries a small plate 86 and the plates are interconnected by bars 98. At the center of each bar there is secured a downwardly extending bracket 100 supporting a bar 102, upon which are mounted two yarn carriers 104. The yarn 106 from these carriers form courses in general parallel to and along the roving courses, and are guided thru the adjustable guides 108 which are secured to a vertical face of the cam ring 72, as shown in Fig. 12. The guides 108 are adjustable in height by means of the slot and bolt connection 110 and to and from the needles by means of the slideable rod 112.

A modified form of yarn carrier is shown in Fig. 13a, wherein the bar 98 carries a T-bar 98' for the reception of two horizontal spools, and a bar 99 for the reception of a single vertical spool 99'. In Fig. 10a there is shown a modified yarn guide wherein the slideable rod 112 supports a closely wound flexible coil spring 112' thru which the yarn is guided. The nozzle end of the spring can be placed to engage the cylinder needles 76 and click thereover in the movement

of the cam ring 72, thus enabling the yarn to be fed exactly to the point desired.

Roving guards 114 are secured to the cam ring 72 and are radially adjustable by means of rods 116. These guards keep the roving out of the cylinder needles, i. e., behind them, so that these needles always reciprocate in front of the roving. A guard 118, having a curved end 120, is positioned in front of the moving guide 84 (in the direction or rotation of the cam ring) so as to push the warp threads and the roving inwardly, so that the next roving course is allowed to enter in front of the threads, to be then knit in.

It will be apparent from the above description that the roving baskets, guides, and guards, as well as the yarn brackets, are rotated about the dial thru the medium of the cam ring, and that the dial cap plate is also correspondingly rotated thru the sleeve 44. As the parts rotate, the roving is drawn into the working area of the needles and is knitted in courses as shown in Figs. 24 and 25, to form a pad or blanket, by the action of the warp threads and interknit yarns.

Referring now to Fig. 7, the numeral 120 indicates a dial cam section, of which there are six bolted or otherwise secured to the dial cap plate as shown. These cam sections are provided with two separate inverted cam tracks as at 122, 124, and each section is similar to each of the other sections. The cam track 122 accommodates fins 126 on the jacks 128, and the track 124 accommodates the conventional cam followers on the dial needles 132. It will be obvious that the jacks and dial needles will thus be reciprocated radially of the dial, in predetermined relation, as the dial cap plate rotates, since the needles and jacks are longitudinally guided in the radial grooves 134 provided in the stationary dial bed for the purpose.

The cylinder needles 76 are stationarily mounted for vertical reciprocation in the usual slots in the cylinder, and are held against radial movement by a peripheral coil spring 76'. Reciprocation is produced by the traveling cams 136, 138, and 140, of which one each is mounted in each section 142 of the cam ring 72. The cams 136, 138, 140 are complemented to form a camming track for the downward motion of the cylinder needles by the cams 144 which are mounted on vertical rods 146 in the cam ring 72. The rods 146 are resiliently supported adjacent stops 148 by springs 150, to prevent possible jamming of the cylinder needles in the cam track.

One dial cam 120 is set to cooperatively actuate the jacks 128 and dial needles 132 in conjunction with each set of the three cylinder cams 136, 138, 140, which of course elevate the cylinder needles 76 three times to each single extension of the jacks and dial needles. This is shown by the high point 156 of jack cam track 122, and high point 158 of dial needle cam track 124. The high points 156 and 158 are offset approximately the length of one cylinder cam so that it will be seen that the jacks and dial needles are extended in sequence and not simultaneously, and in the portion of cam 120, as at 160 in Fig. 7, both jacks and dial needles are recessed for the space of one cylinder cam.

In general, therefore, it may be stated that the jacks will be extended when the cylinder needles are raised by one cam; that the dial needles are extended during the next raise of the cylinder needles; and that both jacks and dial needles are retained retracted during the third and last rise 75 of the cylinder needles in any one section of

three cylinder cams. Of course, in actual design of the cams, the peaks of the jacks and dial needles do not exactly correspond with the peaks of the cylinder needles, but these peaks may be slightly offset to provide for practical operation of the knitting elements, as will be apparent to one skilled in the art.

The dial and cylinder needles are here shown as of the latch type, but spring needles could also be used. The jacks 128, as best illustrated in Figs. 17, 18, and 26 et seq., are each provided with a thin strip of spring metal 162 welded or otherwise secured to one flat face of the jack. The corresponding ends of both jack and spring strip are provided with apertures 164 for the guiding reception of a warp thread, and each of these threads is so guided. The walls of the slots 134 in Figs. 17 and 18 are spaced in an exaggerated manner for clarity, but in reality the walls are spaced to form narrow slots so that when the jacks are retracted, Figs. 20, 22, 31, 32, the spring strip 162 lies flush with the jack, and the thread 62 is closely held in the slot. This effect allows a great number of jacks to be used in a small circumferential area of the dial.

When the jack is extended, Figs. 18, 21, 29, 30 the spring strip 162 will spring away from its jack at the forward end, and spread out the warp thread 62, and a cylinder needle, rising behind the spring strip and to one side thereof, can hook the thread as the jack retreats. This effect is illustrated in Figs. 20-23, and Figs. 27-32, and explains the use and operation of the jacks, which is to feed the warp to the cylinder needles.

In order to explain the operation of the machine, let it be assumed that a dial cam 120 is so arranged with respect to the three cylinder cams 136, 138, 140, as shown in Fig. 14, that with rise of the cylinder needles due to cam 140, the jacks are extended; with rise of the cylinder needles due to cam 138, the dial needles are extended; and with the cylinder needle rise due to cam 136, both jacks and dial needles remain retracted. This is a practical assumption, inasmuch as the jacks operate just prior to the dial needles, and an idle position for both jacks and dial needles follows and precedes these operations. Only one full idle position for both jacks and dial needles follows and precedes these operations. Only one full idle position occurs in each cycle, but whether it is said to follow or precede is immaterial.

The dial needles are always looped by the yarn 106, which runs around the dial, and each jack always accommodates a warp thread, which pass generally radially of the dial. The yarn 106 is guided into the needles by the right hand guide 108, in Fig. 10, and yarn 107 is guided into the cylinder needles by the guide 108 to the left in this figure.

Starting with cam 140, the cylinder needles are looped by the yarn 107, which is a binder yarn, and runs circumferentially of the dial and longitudinally of the roving. The jacks are guiding the warps, as always, and the jacks and cylinder needles extend, so that each such needle comes to position behind a spring strip 162 as above explained. The jacks retreat, the needles hook the warp and descend, casting off the binder yarn 107, to form loop 170, and thus forming a warp loop on the needles. This operation has 70 obviously brought the warp down the distance between the jacks and the tops of the cylinder needle slots, where the loop just mentioned is formed, and this action clearly places a warp thread transversely across and part way around 75

the new course of roving just admitted when the cylinder needles were previously in lowered position. This action is illustrated in Figs. 20-23, the last figure showing the binder yarn 107 in the act of being cast off to form a loop 170.

The cylinder needles now are looped by the warp 62, and rise on cam 136 while the dial needles are extending. The yarn 106 lays in between the alternated extended dial and cylinder needle hooks, and as the dial needles retreat they cast off the old yarn 106 loop, and form a new one at 178. At the same time, the new yarn 106 is carried down across the roving by the cylinder needles, and the warp, which looped these needles, is cast off, forming loop 174. It will be seen from this that the yarn 106 is always carried almost completely around the roving, being interrupted by loops 170, 174, and looping with each adjacent course, forms connections therebetween. This is illustrated as to the courses in the pad in Fig. 24.

Finally, at the range of cam 136, the cylinder needles are now looped by the yarn 106, which, being alternately drawn down across the roving by the cylinder needles, and led back up again to the dial needles, forms a net-like knit weave which somewhat compresses the roving and renders it easier for the next guard 118 to press the knit-in roving back so that the next guide 84 can feed in the next roving. The jacks and dial needles are now idle, and the binder yarn 107 is fed into the cylinder needles, which upon descending, cast off the yarn 106, making loops 176, and form binder loops on the needles ready to be cast off by the next warps on the ensuing cycle.

From the above explanation, it will be seen that binder loops 170 (Fig. 25) are looped and cast off by the warp 62; and the latter is led up between courses to be cast off by a yarn 106 to make a loop at 174. The dial and cylinder needles together form the loops 178, Fig. 24, and yarn 107 casts off yarn 106 to form loop 176. Thus there is a warp thread 62 that travels across and between the courses of roving 88; a thread 107 that travels longitudinally of the courses, and a thread 106 that travels longitudinally of the courses and across them in single spaced loops. These threads are all interknit as described, and form the goods as shown.

Having thus described my invention and the advantages thereof, I do not wish to be limited to the details herein disclosed, otherwise than as set forth in the claims, but what I claim is:

1. In a warp knitting machine, the combination of alternate warp-guiding jacks and needles, said needles being adapted to take a yarn other than said warp; with a second set of needles adapted to knit with said warp and said other yarn in sequence.

2. A warp knitting machine, as recited in claim 1, in which said second set of needles is adapted to knit with a second thread other than said warp during idle periods of both the first needles and the jacks.

3. In a knitting machine, a traveling needle support, a guide on said support for introducing a roving into the machine, a guard for pressing the roving into contact with a previously introduced roving course and to place the roving in position to be knit thereto, and means for knitting the courses of roving together by threads placed transversely and longitudinally of the courses.

4. In a machine for knitting courses of rovings together, means to guide the roving into the machine, means to guide warp yarn adjacent to

the incoming roving, means to guide binder yarn to a position adjacent the warp threads, and means to interknit the warp and binder yarns whereby the former is knit in across the roving and the latter is knit in with the warp but longitudinally of the roving.

5. In a warp knitting machine, warp thread guides arranged remote from the needles, a roving basket arranged in a position over the needles, further warp thread guides adjacent the needles to guide the warp threads around the roving baskets, means to relatively move the baskets and needles, and means to operate the needles, whereby the warp threads and roving are drawn into the machine to be knitted into a fabric.

6. In a warp knitting machine, a framework, a cylinder and dial mounted to rotate in said framework, spaced means to drive said cylinder and dial, a material holding means on said cylinder and dial and extending between said spaced drive means, stationary guide means to lead warp threads around said holding means to reciprocable guide means in the periphery of said dial, needles associated with said cylinder, and means to actuate said reciprocable guide means and said needles.

7. In a warp knitting machine, a dial and cylinder, warp guiding jacks on said dial and needles in said cylinder, means to actuate said jacks and needles in timed relation, material holding baskets mounted to revolve about said cylinder and dial and extending over the dial, warp thread guiding means located near the center of the dial, and further guides adjacent the jacks to lead the threads out of the path of the baskets to said jacks.

8. In a knitting machine, a needle support, needles located in said support for movement to and from operative knitting position, means to so move said needles, warp guiding jacks alternating with said needles, means to move said jacks to and from operative knitting positions, a second support, a series of needles in said second support and adapted to be fed with a yarn thread, and means to move said second named needles to and from operative positions to knit alternately with separate yarns carried by said first named needles and said jacks in series.

9. A knitting machine as recited in claim 8 wherein the operative knitting positions of said first named needles and said jacks are sequentially offset, and said second named needles are active during the operative and inoperative periods of both said first named needles and said jacks.

10. In a warp knitting machine, a series of needles, means to move said needles to and from operative positions, a second series of needles, means to move said last named needles to and from operative positions, a series of warp thread guides, means adapted to reciprocate said guides to and from cooperative positions with said last named needles, and means on said guides effective to spread yarns carried thereby in position to be included within the hooks of said last named needles.

11. In combination with a warp knitting machine having a series of needles and movable cam means for operating said needles; a warp thread guide for each needle, means to reciprocate each guide past its needle, and means associated with each guide to cause a warp thread carried thereby to be extended laterally of said guide in position to be taken by said needle.

12. In a warp knitting machine, the combination of a reciprocal needle and means to reciprocate said needle; of a warp thread guiding jack reciprocable transversely of the path of reciprocation of said needle, and means on said jack effective to extend a thread guided thereby transversely of said jack and in position to be engaged by said needle.

13. In a knitting machine, a needle support, a series of needles located in said support for movement to and from operative knitting positions, means to so move said needles, warp guiding jacks alternating with said needles in said support, means to extend and retract said jacks correspondingly to said needles while the latter are in non-operative positions, a second support movable relatively past said first named support, a series of needles mounted in said second support, means to extend said second named needles to operative positions during the extended periods of both said first named needles and said jacks, and means to retract said second named needles during the retraction of said first named needles and said jacks.

14. A knitting machine as recited in claim 13 including means to extend said second named needles to operative positions during retractive or inoperative positions of both said first named needles and said jacks, the last named positions being of longer duration than the retractive positions of said second named needles.

15. In a knitting machine, the combination of a needle bed, a series of needles in said bed, means to extend said needles to operative position and to retract the same to inoperative position in said bed, a series of warp thread guiding jacks located in said bed alternately with said needles, and means to extend and retract said jacks as a series relative to said bed in alternate relation to the extension and retraction of said needles as a series; of a second needle bed movable relatively past said first named bed, a series of needles in said second named bed, and means to extend said second named needles as a series into operative relation with both said first named needles and said jacks alternately.

16. A knitting machine according to claim 15 wherein the extended and retracted periods of said second named needles are substantially equal, and the retracted periods of said first named needles and said jacks are longer than their extended periods.

17. A knitting machine according to claim 15 wherein the retracted periods of said first named needles and said jacks are longer than their extended periods, said periods overlapping so as to occur for a time simultaneously.

18. A knitting machine according to claim 15 wherein the means to extend and retract both said first named needles and said jacks are effective to hold the same in retracted position longer than in extended position, so that the retracted periods of said first named needles and jacks overlap.

19. A knitting machine according to claim 15 wherein the means to extend and retract both said first named needles and said jacks are effective to hold same in retracted position longer than in extended position to produce a simultaneous retracted period thereof, and said means to extend said second named needles is effective to cause an extension thereof to operative positions during said simultaneous retracted period.

FRANK J. FORD.
